INSTRUMENT FOR SETTING POSITION OF A
TOOL FOR THE GRINDING THEREOFWillard J. Clements, Milwaukee, Wis., assignor to
Wetmore Reamer Company, Milwaukee, Wis.,
a corporation of Wisconsin

Application December 5, 1942, Serial No. 468,012

12 Claims. (Cl. 51—220)

This invention relates to an instrument for setting the position of a tool for the grinding thereof.

Cutting tools, such as those used in boring bars and the like, have to be ground to provide both side rake and back rake. The mounting of the tool in a universal vise for the proper presentation of its face to a grinding wheel has heretofore been a matter requiring a very considerable expenditure of time. On the average, from one half hour to several hours has been spent in positioning a single tool for grinding because of the fact that when the angularity of the surface to be ground is adjusted in one plane, the adjustment upsets an adjustment previously made in a plane at right angles thereto. The present invention seeks to provide means whereby the exact angularity in each of the two planes in which side and back rake is provided may be determined concurrently, thereby reducing to approximately two minutes the time required to position the tool in a fixture for grinding.

The problem is complicated by the fact that different tools are inserted at different angles in their respective boring bars or other supports in which the tools are used. These angles must be allowed for in positioning the tool for grinding, inasmuch as the tool, for convenience, is usually set at right angles to the path of the grinder. It is an object of the invention to provide novel and simple means readily adjustable to determine any desired angles of back and side rake in any desired planes, while allowing for any desired angular relation between the position which the tool occupies while ground and the position which it occupies in use.

More specifically, it is proposed to provide a support with a plurality of arms pivotally adjustable in planes at right angles to each other, each of such arms carrying a spirit level or equivalent to enable the operator to set the support to any desired plane as determined by the levels mounted on the respective arms. In a preferred embodiment of the invention the support upon which the respective arms are pivotally adjustable is itself rotatably adjustable about a third axis normal to the axes upon which the respective arms are movable.

The object and advantages of the invention will be more apparent to those skilled in the art upon analysis of the following disclosure thereof.

In the drawing:

Fig. 1 is a view in perspective of the instrument per se.

Fig. 2 is a view in side elevation of the instru-

ment in use upon a fixture set up in a universal vise on the table of a surface grinder.

Fig. 3 is a view in end elevation of the tool as it appears in the fixture.

Fig. 4 is a view in side elevation of the tool as it appears in the fixture, the latter being fragmentarily illustrated.

Fig. 5 is a view of the tool as it appears in plan when mounted in a boring bar for use, the work being fragmentarily illustrated.

Fig. 6 is a view in perspective of a modified embodiment of the instrument per se.

Like parts are identified by the same reference characters throughout the several views.

The tool 7 is mounted for use in a boring bar 8. The particular mounting may be in accordance with the disclosure of the Hassig Patent 2,227,084 of December 31, 1940. In different boring bars and the like, the tool may project at different angles. That is to say, the axis C—D of the tool may have any desired angular position with respect to the axis upon which the boring bar 8 is rotated respecting the work.

Whatever the angular position of the center line C—D of the tool, it is necessary to provide for predetermined back rake and side rake. The tool is so shaped as to provide cutting edges at 9 and 10. Grinding is done upon the surface 12 which is bounded by the margins 9 and 10 at which cutting occurs. In order that the surface 12 may slope at a desired angle with respect to its path of movement through the work, the surface 12 may be so ground as to be inclined in two directions from a position at right angles to its path of movement. Its back rake, as measured in the plane indicated by the line W—X in Fig. 5, may, for example, be of the order of 10 degrees behind a plane determined by the axis of the boring bar and the radius drawn from such axis to the cutting edge 9. The side rake, as measured along the line Y—Z in Fig. 5, may, for example, range anywhere from 3 degrees to 10 degrees backwardly from the plane determined by the axis of the boring bar and the edge 10 of the tool. The figures given are purely illustrative. Any angle or no angle may be desired.

For grinding, the tool 7 is removed from the boring bar 8 or other carrier and positioned in the fixture block 15. The fixture block has a wedge clamp 16 similar to that provided in the tool carrier, the clamping member 16 being drawn by clamping screw 17 into engagement with the flat side 18 of the tool so that the tool is held in a well defined position in the fixture block 15.

Fixture block 15 is now mounted in a so-called

universal vise which has a base 19, and a tiltable table 20 pivotally adjustable with respect to the base and adapted to be secured in adjustment by a clamp nut 21. The vise table 20 carries a stationary clamp jaw 22 and a movable clamp jaw 23 adjustable by means of the vise screw 24. The fixture block 15 is clamped between the jaws 22 and 23 to hold the tool 7 in a position where the surface 12 thereof can be exposed for grinding. The base 19 is then mounted on the table 25 of a surface grinder for translative movement with respect to the grinding wheel 26, it being obvious that although the grinder table is ordinarily the part which travels, the wheel might have translative movement so far as this invention is concerned.

While the vise itself is not per se universal, having but a single axis of adjustment, it provides for universal adjustment of the block 15 in which the tool 7 is mounted for grinding. The base 19 may be set at any desired position on the grinder table 25, thus giving adjustment on one axis. The vise table 20 is pivotal on the axis of clamp 21 with respect to the vise base 19 to provide for a second axis of adjustment, and the fixture block 15 may be adjusted between the jaws 22 and 23 to provide for a third axis of adjustment. Since the vise base 19 will ordinarily be located in parallelism with the path of relative movement of the grinding wheel and the grinder table, the present invention is primarily concerned with adjustment effective about the axis of the vise clamp 21 and pivotal adjustment at right angles thereto in the plane determined by the opposing faces of the vise jaws 22 and 23.

Because the tool 7, as mounted in the fixture block 15 in the vise, does not have the same angle at which the tool is located in its boring bar or other carrier (and because the latter angle varies widely in different equipment) it is necessary to provide some means for determining back rake and side rake with due regard to the angle at which the tool is actually used. For the purposes of the preferred instrument shown in Fig. 1, I provide my fixture block 15 with a pair of spaced parallel guide rails 27 and 28 projecting upwardly from its upper surface 29.

My improved instrument has a base 30 which is made to fit accurately between the rails 27 and 28 to assure parallelism of the base with the axis of tool 7 when the instrument is mounted on the fixture block 15.

Swiveled in the base 30 is an upstanding post 31 which is preferably exactly normal to the base 30. The base 30 may be slotted at 32 and provided with a tension screw 33 for clamping the base with any desired degree of pressure upon the post 31 to determine the frictional resistance to the rotation of the post, whereby the post tends to remain in any position to which it is adjusted. The post may carry a dial at 34 and the base may be provided with a calibrated scale at 35 cooperating with the dial to indicate the particular angle of rotative adjustment of the post 31 respecting the base.

At the upper end of post 31 is a head 48 from which a pair of brackets 41 and 42 project at right angles. Pivoted to these brackets are arms 43 and 44 respectively. Clamping nuts 45 and 46 upon the pivot bolts hold the arms releasably in any position to which they are manually adjustable. Each arm is provided with a mark at 47 which serves as a pointer. The pointer

of arm 43 moves across a calibrated scale at 48, while the pointer portion of arm 44 moves across a calibrated scale 49. The scales 48 and 49 are calibrated preferably in degrees, although arbitrary calibrations may be employed. While different arrangements are possible, within the contemplation of this invention, the particular organization disclosed, in which both arms are pivoted at their outer ends to the respective brackets, is such that both scales read upwardly in a positive direction.

Each of the respective arms 43 and 44 is provided with a spirit level at 50.

The instrument is used in the following manner.

First, the dial 34 carried by the post 31 is rotated with respect to the calibrated scale 35 on the base to set the post at the exact angle between the position at which the tool axis is supported in the fixture for grinding and the position which the tool axis occupies when the tool is mounted in its boring bar or other carrier for use. In the device illustrated, that angle is approximately 40 degrees.

Secondly, the pivoted arm 43 is adjusted with respect to its scale 48 to the exact back rake angle desired, such angle being shown by the graduations or calibrations of the scale 48. Then the arm 44 is adjusted with respect to its scale 49 to the exact side rake angle desired, such angle being indicated by the calibrations of scale 49.

With the instrument positioned on the fixture block 15 between the guides 27 and 28, and the jaw 23 and the clamping nut 21 sufficiently loose to permit the block to be manipulated, the block, already containing the tool to be ground, is raised and lowered about the axis of the clamping nut 21 and is tilted about the right angle axis defined by the parallel surfaces of jaws 22 and 23 until the bubbles of the spirit levels 50 in both of the arms 43 and 44 show that the block is positioned in the proper plane for grinding. When such a position is reached the bubbles in the spirit glasses will be centered in the glasses. The clamps are now tightened and, if desired, the instrument may be removed from the fixture block and the grinder is operated to cause the wheel 26 to traverse the face 12, thereby grinding such face to exactly the desired plane.

It will be noted that the arms 43 and 44 are not adjustable in the same planes in which the block 15 and the tool are adjusted in the vise. Nevertheless, the planes in which the arms 43 and 44 have their pivotal movement are, preferably, at least, the identical planes in which the angles of back rake and side rake are measured. The fact that the adjustments of the tool in the vise are effected in totally different planes complicates the problem but is requisite to enable standard vise and grinding equipment to be used. It is because of this discrepancy between the plane of adjustment and the plane of measurement that great difficulty has heretofore been experienced. However, by manipulating all adjustments concurrently (as is possible where it is only necessary to read the level as distinguished from taking an actual measurement in degrees) the exact plane of desired grinding is very readily established regardless of the directions in which the adjustments are effected.

The method may be practiced irrespective of any particular tool by setting spirit levels at an angle (preferably a right angle) to each other

and then tilting them to the desired back and side rake angles respectively. With the levels thus tilted in fixed positions regarding the work face to be ground, it will be apparent that when the levels are adjusted to horizontal, the work face will occupy the desired grinding plane.

At the expense of some convenience, it is possible to simplify the instrument in the manner suggested in Fig. 6. In this construction the arms 43, 44, and their mountings, are identical with those previously described. In this instance, however, a single unitary part 55 is flanged at 56 to provide a base and it has portions 57 and 58 at right angles to each other to carry the pivot poles upon which the arms 43 and 44 are adjustable subject to the clamping pressure of the thumb nuts 45 and 46. Since the portions 57 and 58 are at right angles to each other, it is possible to adjust the whole body 55 of the instrument by means of a protractor upon the flat surface of a fixture block in which the tool is mounted. In other words, the guide rails 27 and 28 would preferably be omitted from the fixture block 15 if this type of instrument were to be used, and the body 55 would simply be set by protractor on the top of the block at the desired angle to locate the arms 43 and 44 so that these would swing in the planes in which the back rake and side rake should be measured. Naturally, it is preferred to use the Fig. 1 construction in which the swiveling of the post 31 and the provision of the scale 35 permit this angle to be determined without any separate protractor or other accessory tool.

I believe that those skilled in the art will readily appreciate that a variety of changes may be made in the specific instrument herein disclosed without departing from the concept as above outlined.

I claim:

1. A setting guide for tool holders, comprising a base adapted to be mounted upon a tool holder in a predetermined relation to a tool carried thereby, an upright post swiveled in said base for rotative adjustment about its own axis, bracket means mounted on said post, arms pivoted to said bracket means for adjustment in angularly related planes which are upright respecting said base, and level indicating devices carried by the respective arms whereby to define when level a predetermined plane for said base.

2. A setting guide for tool holders, comprising the combination with bracket means of angular form, of arms mounted for pivotal adjustment at remote points on said bracket means and projecting toward a common apex, calibrated scale means with respect to which the free ends of said arms are pivotally adjustable, level means carried by the respective arms, and means for mounting said guide on a tool holder with said arms extending at predetermined angles to the axis of a tool carried by the holder.

3. A setting guide for tool holders, comprising bracket means having faces joined approximately at right angles, in combination with arms pivoted to the bracket means at points remote from the juncture of said faces and having free end portions extending toward such juncture, clamp means for maintaining the arms in predetermined pivotal adjustment upon their respective faces, said arms and faces having interacting gauge means for indicating the respective positions of said arms, and spirit levels carried by the respective arms whereby the leveling of said arms in predetermined positions of angular adjustment

will determine the position of said bracket means with reference to a horizontal plane, said bracket means being mountable upon a tool holder, with said faces extending at equal angles to the axis of a tool carried by the holder.

4. In tool grinding equipment, the combination with a base having a swivel clamp, of an upright post swiveled in said clamp, said post and base having coacting calibrations indicating the angle of position of the post, bracket members carried by the post above the base and angularly related to each other, pivot bolts carried by the bracket heads at points remote from the post, arms mounted on said pivot bolts and having free end portions projecting therefrom toward the post, clamp means for fixing the angular adjustment of the respective arms upon their respective bolts, and means providing an indicating scale showing the angular adjustments of the respective arms, each of said arms being provided with a spirit level, and means for mounting a tool in fixed relation to said base and adjusting the base to a position in a grinding place with each of said arms in a level position.

5. The combination with a fixture adapted to hold a tool for grinding of a base keyed to the fixture in a predetermined position with reference to a tool thereon, bracket means comprising angularly related divergent arms mounted on said base, said arms being adjustable about an axis perpendicular to the base, lever arms pivotally adjustable in upright angularly related planes with respect to the bracket arms, said bracket arms and lever arms having coacting calibrated

scale means for indicating the angular positions in such planes of the respective lever arms, and level means carried by the respective lever arms whereby to facilitate adjusting the tool with one of its faces in a grinding plane tilted in two directions from a horizontal plane.

6. The device set forth in claim 5, in which said bracket arms are at right angles to each other and are positively pivoted for pivotal movement with respect to the fixture about an axis at right angles to both of said arms.

7. The combination with a fixture for supporting a tool for grinding, of a base, said base and fixture being formed for interlocking engagement whereby to define a particular base position on said fixture, a tool clamp carried by said fixture and adapted to hold a tool in a predetermined position with reference to said base, bracket means providing a pair of divergent arms, means pivoting the bracket means to the base for adjustment upon an axis extending away from said fixture, a pair of lever arms pivoted to the bracket arms at points remote from said axis and projecting toward said axis, levels carried by the respective lever arms, and means for positioning the lever arms at predetermined angles in their pivotal adjustment respecting the bracket arms, the adjustment of the bracket arms to a particular angular position about the first mentioned axis, and the adjustment of the lever arms to predetermined angular positions of pivotal adjustment with reference to their respective bracket arms, followed by the leveling of both of the lever arms being adapted to establish a predetermined position for a tool mounted in said fixture.

8. An instrument for setting a tool with one of its faces in a grinding plane comprising the combination with a tool holder having a tool receiving socket and a supporting surface in a predetermined position with reference to said

socket of an angle bracket flanged to comprise a base, pivot posts projecting from angularly related portions of said bracket, levers pivoted to said posts, and spirit levels mounted on said levers, said bracket being adjustable on the tool holder to a position with said levers extending at equal angles to a plane which includes the axis of the tool receiving socket.

9. Tool grinding equipment including the combination of a tool holder provided with means for securing a tool in fixed relation to a grinding plane, a setting guide for the tool holder, a pair of supports thereon adapted for independent swinging adjustments in divergent planes, calibrating means associated with each support for indicating its pitch with reference to a horizontal plane, a tubular level carried by each support, means for mounting the setting guide on the tool holder with its levels extending in planes at predetermined angles to the axial line of the tool, and means for adjusting the tool holder to bring both levels to a horizontal position.

10. Tool grinding equipment, including the combination with a tool holder provided with means for rigidly securing a tool thereto, of means to predetermine the pitch of the tool surface to be ground, including a setting guide provided with a pair of calibrated pitch indicators extending in planes oppositely divergent from a common apex, said guide being mountable on the tool holder with such apex in a plane which coincides with the axis of the tool, and means for adjusting the tool holder to bring said surface of the tool to a pitch in correspondence with that predetermined by the pitch indicators, and level indicating means associated with the pitch indicators, whereby the proper adjustment of the tool holder may be visually determined.

11. In a tool grinding apparatus, the combination with a tool holder provided with means for rigidly securing a tool thereto with one of its surfaces in fixed relation to a grinding surface, said tool holder being provided with a mounting for a setting guide, a setting guide having a base adapted to fit said mounting, a set of level supports mounted on the guide and adapted to be tiltably adjusted in planes oppositely divergent from a plane which includes the axis of such tool, levels, each carried by one of said supports, means for separately adjusting the supports to a predetermined pitch with reference to the base of the setting guide, and means for adjusting the tool holder to bring said supports to a position in which the levels indicate a horizontal plane.

12. In a tool grinding apparatus, the combination with a tool holder provided with means for rigidly securing a tool thereto with one of its surfaces in fixed relation to a grinding surface, said tool holder being provided with a mounting for a setting guide, a setting guide having a base adapted to fit said mounting, calibrated pitch indicators carried by the setting guide and adjustable in planes divergent in opposite directions from the axis of a tool secured to the holder as aforesaid, means for adjusting the tool holder to a position in which the tool face to be ground is pitched from a horizontal plane in the directions determined by the pitch indicators, and level indicating means associated with the pitch indicators, whereby the proper adjustments of the tool holder may be visually determined.

WILLARD J. CLEMENTS.
